UNITED STATES PATENT OFFICE.

EDWIN C. WOLFF, OF PHILADELPHIA, PENNSYLVANIA.

FIXTURE STAND.

Application filed July 29, 1924. Serial No. 728,823.

To all whom it may concern:

Be it known that I, EDWIN C. WOLFF, a citizen of the United States, residing at Philadelphia, in the county of Philadelphia and State of Pennsylvania, have invented certain new and useful Improvements in Fixture Stands, of which the following is a specification.

My invention relates to fixture stands and its objects are to provide a stand which will enclose articles such as a telephone when not in use, which when opened will shift the article from within the stand for convenient use; which will firmly support a fixture; which may be made in various shapes without affecting the moving parts therein, and which will have doors so mounted therein that when in closed position they will be practically unnoticeable.

These objects, and other advantageous ends which will be described hereinafter, I attain in the following manner, reference being had to the accompanying drawings in which

Figure 1 is a front elevation of a fixture stand constructed in accordance with my invention and having a fixture attached thereto,

Figure 2 an enlarged fragmentary section on line 2—2 of Figure 1,

Figure 3 a section on line 3—3 of Figure 2,

Figure 4 an enlarged section taken on line 4—4 of Figure 2, and

Figure 5 an enlarged section taken on line 5—5 of Figure 2 illustrating the parts moved into another position.

Referring to the drawings, 1 indicates a fixture stand, preferably cylindrical but may be of other shapes, indicated in dot-and-dash lines at 2, 3 a fixture support secured to the stand and 4 a fixture, preferably a lamp fixture, mounted on the support. The fixture stand has an open-ended casing 5 provided with an entrance opening 6. A

top plate 7 closes the upper end of the casing and a bottom plate 8 closes the lower end of the casing. Arms 9 pivoted to plate 7 at 10 are secured to the upper edges of a pair of doors 11 of arcuate cross sections.

Arms 12 pivoted to the lower plate at 13 are secured to the lower edge of doors 11. Doors 11 swing on the pivots 10 and 13 alongside the walls of the casing 5. A guide

14, secured to the lower plate 8, slidably supports a platform 15 which is adapted to carry articles, such as a telephone 16, partly

out of the casing as shown in Figure 5. The sliding movement is imparted to the platform by extensions 17, fixed to lower arms 12, radiating from pivot 13, and provided with pins 18 adapted to engage between a pair of lugs 19 on the under side of the platform. When the doors are swung open, extensions 17 will swing to bring their pins 18 between lugs 19 indicated in dot-and-dash lines at 20 in Figure 3 and move the platform partly out of the casing into the position shown in dot-and-dash lines at 21 and full lines in Figure 5. The telephone on the platform will then be in convenient position for use. Fixture support 3 includes a pipe 22 screwed into a spacing member 23 which is screwed into a boss 24 integral with top plate 7. Spacing member 23 allows wires 25 to pass into pipe 22. The lamp fixture 4 is mounted on pipe 22 in any suitable manner. A hood 26 is placed over pipe 22 so that it covers top plate 7 and the parts connected therewith.

To use the telephone, either of tongues 27 integral with lower arm 12 is moved away from the other to open doors 11 as shown in Figure 5. This movement brings extensions 17 with their pins 18 between the lugs 19 on the bottom of the platform, and moves the platform partly out of the casing as shown in dot-and-dash lines at 21 in Figure 3 and in full lines in Figure 5. The platform in this position supports the telephone in a convenient position for use. After use, tongues 27 are brought together again to bring the doors into closed position. This movement causes the platform to move into its former position in the casing.

The fixture stand above set forth performs the dual function of enclosing articles and supporting a fixture. Doors mounted as above described are practically unnoticeable in closed position.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A fixture stand including an open-ended

casing having an entrance opening; a plate closing the upper end of the casing; a plate closing the lower end of the casing; arms pivoted on the plates; doors mounted on the 5 arms and adapted to swing into position to close the opening; a guide secured to the lower plate; a platform slidable on to the guide; extensions on the arms, and lugs on the platform adapted to be engaged by the 10 extensions to cause the platform to move outwardly when the doors are swung into open position.

2. A fixture stand including an open-ended casing having an entrance opening; a plate 15 closing the upper end of the casing; a plate closing the lower end of the casing; arms pivoted on the plates; doors mounted on the arms and adapted to swing into position to close the opening; a guide secured to the 20 lower plate; a platform slidable on to the guide, and means on the arms operatively connected with the platform whereby moving the doors into open position will cause the platform to move outwardly.

25 3. A fixture stand including an open-ended casing having an entrance opening; a plate closing the upper end of the casing; a plate closing the lower end of the casing; arms pivoted on the plates; doors mounted on the 30 arms and adapted to swing into position to close the opening; a platform support mounted on the lower plate; a platform movably mounted on the support, and means operatively connecting the arms with the 35 platform whereby moving the doors into open position will cause the platform to move outwardly.

4. A fixture stand including a casing having an entrance opening; arms pivoted to the 40 upper and lower part of the casing; doors mounted on the arms and adapted to swing

into position to close the opening; a platform movably mounted on the lower part of the casing; extensions on the arms, and lugs on the platform adapted to be engaged by the 45 arms to move the platform outwardly when the doors are swung into open position.

5. A fixture stand including a casing having an entrance opening; arms pivoted to the upper and lower part of the casing; doors mounted on the arms and adapted to swing into position to close the opening; a platform movably mounted on the lower part of the casing; extensions on the arms, and means projecting from the platform 50 adapted to be engaged by the arms to move the platform outwardly when the doors are swung into open position.

6. A fixture stand including a casing having an entrance opening; arms pivoted to the upper and lower part of the casing; doors mounted on the arms and adapted to swing into position to close the opening; a platform movably mounted on the lower part 60 of the casing, and means operatively connecting the arms with the platform whereby moving the doors into the open position will cause the platform to move outwardly.

7. A fixture stand including a casing having an entrance opening; arms pivoted to the 70 upper and lower part of the casing; doors mounted on the arms and adapted to swing into position to close the opening; a platform movably mounted on the lower part of the casing, and extensions on the 75 arms operatively connected with the platform whereby moving the doors into open position will cause the platform to move outwardly.

In testimony whereof I have signed my 80 name to this specification.

EDWIN C. WOLFF.
